HAND BRAKE

Roland J. Olander, Chicago, Ill., assignor to W. H. Miner, Inc., Chicago, Ill., a corporation of Delaware

Application January 12, 1933. Serial No. 651,263

20 Claims. (Cl. 74—112)

This invention relates to improvements in hand brakes.

One object of the invention is to provide a hand brake mechanism wherein spinning of the usual 5 operating hand wheel is prevented during release of the brakes, thereby protecting the brakeman from injury.

A further object of the invention is to provide, in a hand brake of the character described in the 10 preceding paragraph, means controlled by rotation of the hand wheel in brake-tightening direction to operatively connect the hand wheel to and disconnect the same from the usual winding mechanism so that the latter will be automatically thrown into operation when the hand wheel 15 is rotated in chain-winding direction and will be automatically completely released, without spinning of the hand wheel, by initial rotation of the hand wheel in chain-unwinding direction.

20 A more specific object of the invention is to provide, in a hand brake mechanism of the power-multiplying, worm gear operated type, clutch means controlled by rotation of the hand wheel 25 in one direction for operatively connecting the worm gear to the usual chain-winding drum and controlled by rotation of the hand wheel in a reverse direction for disconnecting the worm gear and drum to permit free rotation of the latter to release the brakes.

30 Other objects of the invention will more clearly appear from the description and claims herein-after following.

In the drawings, forming a part of this specification, Figure 1 is a vertical sectional view of a hand brake mechanism, illustrating my improvements in connection therewith, the hand brake mechanism being shown as mounted on the vertical end wall of a railway car, and the section being in a plane parallel to said wall. Figure 2 is a vertical sectional view, corresponding substantially to the line 2—2 of Figure 1. Figure 3 is a horizontal sectional view, corresponding substantially to the line 3—3 of Figure 1. Figure 4 is an elevational view, partly broken away, looking toward the right in Figure 1, illustrating one position of a certain weighted lever. Figure 5 is a view similar to Figure 1, partly broken away, showing the parts in a different position. Figure 6 is a view similar to Figure 3 but showing the parts in the position illustrated in Figure 5. Figure 7 is a view similar to Figure 4 but showing the weighted lever in another position. And Figure 8 is a view similar to Figure 3, showing the weighted lever in the position illustrated in Figure 7.

In said drawings, the improved hand brake mechanism is illustrated as enclosed in a housing 10 mounted on the vertical end wall of a railway car by means of bolts 11—11 or similar securing members extending through lugs 12—12 on the 60 rear wall of the housing.

My improved hand brake mechanism comprises broadly a chain-winding drum A; a worm wheel B; a worm C; a hand wheel D; a sliding clutch element E; a clutch spring F; a clutch operating lever G; a rotary actuating member H for the lever G; and a weighted lever K.

The chain-winding drum A is hollow, as clearly shown in Figure 1, and has cylindrical bearing portions 13 and 14 at opposite ends journaled 70 respectively in bearing seats 15 and 16 provided in the vertical end wall 17 and partition wall 18 of the housing 10. The diameter of the bearing portion 14 is greater than that of the bearing portion 13, and the drum is provided with interior clutch projections at the end which has the bearing portion 14. The brake chain, which is indicated by 19, is wound on the drum A in the usual manner and has one end thereof fixed to the drum by means of a pin 20 extending through 75 a pair of lugs 21—21 and the end link of the chain 19, which end link is disposed between the lugs 21—21. The lugs 21—21 are formed integral with the chain-winding drum A.

80 The worm wheel B has oppositely projecting, cylindrical hub portions 22—22, which are journaled in bearings 23—23 provided on the partition wall 18 and the end wall 24 of the main body portion of the housing 10. As clearly shown 85 in Figure 1, the bearing 23, which is carried by 90 the partition wall 18 of the housing, forms a continuation of the bearing 16 but is of smaller diameter than said last named bearing. The worm wheel B is provided with an axial opening 25, which extends through the hub portions of the 95 worm wheel.

The worm C is disposed below the worm wheel B and meshes therewith. The opposite ends of the worm C are journaled in bearings provided 100 in the front and rear walls of the housing, and the hand wheel D is fixed to the outer end of said worm, as clearly illustrated in Figures 2 and 3. The hand wheel is also indicated in dotted lines in Figure 1.

105 The sliding clutch element E is in the form of a shaft having a clutch head 26 at the inner end thereof provided with a plurality of clutch projections engageable with the interior clutch projections of the chain-winding drum A. The 110 clutch element E projects beyond the bearing

23 and has a disc, forming an annular flange 27, secured to the outer end thereof. The clutch element E is slidable within the opening 25 of the worm wheel B and has longitudinally extending ribs 28-28, which engage within similarly formed grooves 29-29 on the interior walls of the opening 25 of the worm wheel B. The inter-engaging ribs 28 and grooves 29 provide for rotation of the clutch element E in unison with the worm wheel B.

24 The clutch spring F is disposed within the hollow portion of the drum A and has its opposite ends bearing respectively on the clutch head 26 and a wall section 30 of the bearing member 15. The spring F is under compression so that it normally holds the clutch element E in the position shown in Figure 1, that is, with the projections of the clutch head 26 engaged with the projections of the chain-winding drum A. 20 As will be evident when the clutch is thus engaged, the chain-winding drum is rotated in unison with the worm wheel B when the latter is actuated through rotation of the worm C.

25 The clutch operating lever G and the rotary actuating member H are disposed within a chamber 31 provided at the left-hand side of the housing 10, as clearly illustrated in Figure 1. The lever G is pivoted between its ends on a bolt 32, which extends through one of the walls of the chamber 31 and a lug 33 projecting from the wall 24 of the main body portion of the housing 10. The upper arm 34 of the lever G is laterally offset, as clearly shown in Figure 1, and has a fork 35 at the upper end engaging with the flange 27 of the clutch element E, thereby operatively connecting the lever G to the clutch element for shifting the latter. The lower arm 36 of the lever G is engaged by and actuated through the member H.

26 The actuating member H is in the form of a disc having an interrupted set of worm gear teeth 37, which are adapted to mesh with the threads of the worm C. To one side of the set of teeth 37, the disc of the actuating member H is provided with an opening 38 into which the lower end of the arm 36 of the lever G projects. The opening 38 is provided with opposed side walls 39 and 40, which form abutment shoulders adapted to engage the arm 36 to swing the lever G when the actuating member H is oscillated. On the inner side, the disc portion of the actuating member H is provided with a substantially radial stop projection or rib 41, which cooperates with the weighted lever K. The rotary actuating member H is journaled on a short shaft 42 which has its lower end supported in a bearing socket 43 provided on the bottom wall of the chamber 31.

27 The weighted lever K comprises a horizontally disposed shaft 44, a lever arm 45 fixed to said shaft interiorly of the chamber 31, and a weighted lever arm 46 fixed to the outer end of said shaft. The arm 45 of the lever K is provided with a head 47 having oppositely projecting fingers 48 and 49, which are adapted to engage with the rib 41 of the actuating member H. The finger 48 is of lesser width than the finger 49, as clearly shown in Figure 5, and the member H has a raised portion 148 on which the finger 48 may ride to prevent accidental engagement of the latter with the right-hand side of the rib 41 as viewed in Figure 7. As clearly illustrated in Figure 4, the weighted arm 46 of the lever K projects in the same direction from the shaft 44 as the arm 45 so that the finger 49 of the arm 45 will engage with the rib 41 of the member

H and will be maintained in that position by the weighted arm 46. The shaft 44 is supported at its outer end in a bearing opening 50 provided in the outer vertical wall of the chamber 31 and has its inner end supported in an opening in the wall 24 of the main body portion of the housing 10. The shaft 44 also forms a support for the upper end of the shaft 42, the shaft 42 being provided with a transverse opening 51 through which the shaft 44 extends.

28 The operation of my improved hand brake mechanism in applying the brakes is as follows: With the parts in the position shown in Figures 1, 2, 3, and 4, the hand wheel D is rotated in a clockwise direction, as viewed in Figure 1, thereby rotating the worm C and the intermeshing worm wheel B. Inasmuch as the clutch element E is rotatable in unison with the worm wheel B and, as shown in Figures 1 to 4 inclusive, is engaged with the chain-winding drum A, the latter also will be rotated, thereby effecting winding of the chain and tightening of the brakes. During this operation, the weighted lever K is in the position shown in Figure 4, thereby pressing the finger 49 of the head 47 of the lever arm 45 against the rib 41 of the member H and tending to rotate the latter in a direction to bring the interrupted set of teeth 37 thereof into operative engagement with the threads of the worm C. Inasmuch as the worm C is provided with left-hand threads, as clearly shown in Figure 3, rotation of the worm while the brakes are being applied will prevent the teeth of the actuating member H from being engaged with the threads of the worm, because the end thread of the latter will cam over the first tooth of the actuating member H. However, rotation of the worm C in a reverse direction will cause the threads thereof to engage with the interrupted set of teeth 37 of the member H and effect rotation of the latter in a clockwise direction, as viewed in Figure 3.

29 In releasing the brakes, the hand wheel D is rotated in a counterclockwise direction, as viewed in Figure 1, thereby effecting rotation 120 of the worm wheel B in a direction reverse to that produced while the brakes are being applied. During the counterclockwise rotation of the worm C, the interrupted set of teeth 37 of the actuating member H will be brought into 125 engagement with the threads of the worm C through the action of the weighted lever K, as hereinbefore described. Further rotation of the hand wheel D in chain-unwinding direction will cause the actuating member H to be rotated to 130 the position shown in Figure 6, thereby forcing the lever arm 36 of the lever G to the left, as viewed in Figures 5 and 6. The swinging movement of the lever G thus produced will force the clutch element E toward the right, as viewed in 135 Figures 1 and 5, and disengage the clutch head 26 from the clutch projections of the chain-winding drum A, as clearly shown in Figure 5. When the parts have assumed this position, the chain-winding drum is free to rotate and instantaneous release of the brakes is had without any rotation or spinning of the hand wheel D.

30 In applying the brakes with the parts left in the position shown in Figures 5 and 6, it is merely necessary to rotate the hand wheel in a clockwise 145 direction, as viewed in Figure 1. Initial rotation of the hand wheel D and the worm C in this direction will cause rotation of both the worm wheel B and the actuating member H. Rotation of the worm wheel B and the actuating member 150

H will be in a direction reverse to that when the brakes are being tightened, thereby causing the member H to rotate from the position shown in Figure 6 to that shown in Figure 3. During such rotation of the member H, the shoulder 39 thereof will engage the arm 36 of the lever G and swing the same from the position shown in Figure 5 to that shown in Figure 1, thereby re-engaging the clutch head 26 with the clutch projections of the chain-winding drum A. When the parts are in this position, the interrupted set of teeth 37 of the actuating member H will clear the innermost thread of the worm C, thereby permitting further rotation of the worm C without effecting any further movement of the member H, the lever G, and the clutch element E. In this connection, it is pointed out that the clutch spring F is auxiliary to the lever G in bringing the clutch head 26 of the clutch element E into engagement with the clutch projections of the chain-winding drum A. The spring F will seat the projections of the clutch head 26 between the projections of the chain-winding drum A as soon as these parts properly register.

My improved brake mechanism may also be operated to apply and release the brakes without disengaging the clutch element E from the drum, thereby permitting complete backing off of the brakes. In order to operate my improved mechanism in this manner with the clutch engaged, as shown in Figures 1 to 4 inclusive, the weighted lever K is swung from the position shown in Figure 4 to that shown in Figures 7 and 8. As clearly shown in Figure 7, the finger 48 of the arm 45 of the lever K is in engagement with the rib 41 of the actuating member H, thereby holding the shoulder 39 against the arm 36 of the lever G and maintaining the toothed section 37 of the member H spaced from the innermost thread of the worm C, as shown in Figure 8. In view of the fact that the clutch operating lever G is at this time in its outermost position and held against movement by the clutch head 26 of the clutch element E being seated against the corresponding hub section of the worm wheel B, the weighted lever K will be supported and held against movement in the position shown in Figure 7. The teeth 37 of the actuating member H will thus be held out of contact with the worm C until the weighted lever K is shifted back to the position shown in Figure 4. As will be evident when the lever K is in the position shown in Figures 7 and 8, the worm C may be rotated in either direction without engaging the teeth of the actuating member H, thereby permitting the chain to be fully wound on the drum A and unwound from the same without operating the clutch element E. In order to again render the clutch operative, it is merely necessary to throw the weighted lever K back to the position shown in Figures 1 to 4 inclusive. To prevent disengagement of the finger 49 of the lever K from the rib 41 of the actuating member H when the lever swings downwardly from the position shown in Figure 4, a stop lug 52 is provided on the housing 10. Downward movement of the weighted outer end of the arm 46 of the lever K is arrested by engagement with the lug 52. The clearance provided between the outer end of the lever 46 and the lug 52, as shown in Figure 4, is sufficient to permit the required movement of the lever in forcing the toothed section 37 of the actuating member H into the path of the threads of the worm C, but is not sufficient to allow the finger 49 to swing up-

wardly out of the path of movement of the rib 41 of the actuating member H.

In effecting quick release of the brakes by disconnecting the winding drum A from the driving worm wheel B smooth and easy operation of the clutch element E is ensured by relieving the latter of all binding strains through delay action of the clutch while easing off the load on the brake chain by partial unwinding of the latter. This delayed action of the clutch is produced by providing lost motion between the arm 36 of the lever G and the actuating member H while the latter is rotated from the position shown in Figure 3 to that shown in Figure 6. With the clutch engaged and the parts in the position shown in Figure 3, the shoulder 40 of the member H is spaced from the lever arm 36, and the clutch operating lever arm 36 will remain stationary during the unwinding of the brake chain until the actuating member has been rotated to such an extent that the abutment shoulder 40 engages the arm 36 of the lever G and swings the same to operate the clutch.

From the preceding description taken in connection with the drawings, it will be evident that I have provided a hand brake mechanism so designed that the brakeman is fully protected from injury which might occur if the hand wheel were permitted to spin while the brakes are being released and wherein the operation of the brakes is controlled entirely by the hand wheel.

I have herein shown and described what I now consider the preferred manner of carrying out my invention, but the same is merely illustrative and I contemplate all changes and modifications that come within the scope of the claims appended hereto.

I claim:

1. In a hand brake mechanism, the combination with a rotary chain-winding member; of a rotary driving member; a clutch operatively connecting said winding member and driving member; manually actuated means operatively connected to said driving member for rotating the same in reverse directions; and movable means 115 operated by said manually actuated means for engaging and disengaging said clutch.

2. In a hand brake mechanism, the combination with a rotary chain-winding member; of a rotary driving member; a reciprocating clutch 125 operatively connecting said winding member and driving member; manually actuated means operatively connected to said driving member for rotating the same in reverse directions; and lever means operated by said manually actuated means 130 for reciprocating the clutch.

3. In a hand brake mechanism, the combination with a rotary chain-winding member; of a rotary driving member; a clutch operatively connecting said winding member and driving member; manually actuated means operatively connected to said driving member for rotating the same in reverse directions; movable means operated by said manually actuated means for engaging and disengaging said clutch; and means 145 for throwing said movable means out of operation whereby the clutch means remains engaged during both application and release of the brakes.

4. In a hand brake mechanism, the combination with a rotary chain-winding member; of a rotary driving member; a reciprocating clutch operatively connecting said winding member and driving member; manually actuated means operatively connected to said driving member for rotating the same in reverse directions; a lever for 150

- reciprocating said clutch; and movable means operated by said manually actuated means for oscillating the lever to actuate the clutch.

5. In a hand brake mechanism, the combination with a rotary chain-winding member; of a rotary driving member; a reciprocating clutch operatively connecting said winding member and driving member; manually actuated means operatively connected to said driving member for rotating the same in reverse directions; a lever for reciprocating said clutch; movable means operated by said manually actuated means for oscillating the lever to actuate the clutch; and means for throwing said movable means out of operation whereby the clutch remains engaged during both application and release of the brakes. 80

10 6. In a hand brake mechanism, the combination with a rotary chain-winding member; of a rotary driving member; a reciprocating clutch operatively connecting said winding member and driving member; manually actuated means operated by said manually actuated means for oscillating the lever to actuate the clutch; and means for throwing said movable means out of operation whereby the clutch remains engaged during both application and release of the brakes. 90

15 7. In a hand brake mechanism, the combination with a rotary chain-winding member; of a rotary driving member; a reciprocating clutch operatively connecting said winding member and driving member; manually actuated means operated by said manually actuated means for oscillating the lever to operate the clutch. 95

20 8. In a hand brake mechanism, the combination with a rotary chain-winding member; of a rotary driving member; a reciprocating clutch operatively connecting said winding member and driving member; manually actuated means operated by said manually actuated means for oscillating the lever to operate the clutch; and manually controlled displaceable means operative in one position for holding said movable means out of engagement with said manually actuated means. 100

25 9. In a hand brake mechanism, the combination with a rotary chain-winding member; of a rotary driving member; a reciprocating clutch operatively connecting said winding member and driving member; manually actuated means operated by said manually actuated means for oscillating the lever to operate the clutch; and manually controlled displaceable means operative in one position for holding said movable means out of engagement with said manually actuated means. 105

30 10. In a hand brake mechanism, the combination with a rotary chain-winding member; of a rotary driving member; a reciprocating clutch operatively connecting said winding member and driving member; manually actuated means operated by said manually actuated means for oscillating the lever to operate the clutch; and manually controlled displaceable means operative in one position for holding said movable means out of engagement with said manually actuated means. 110

35 11. In a hand brake mechanism, the combination with a rotary chain-winding member; of a rotary driving member; a reciprocating clutch operatively connecting said winding member and driving member; a manually actuated worm member operatively meshing with said driving member for rotating the same in reverse directions; a pivoted lever for reciprocating said clutch; an oscillatory gear having interrupted teeth engageable with the worm member to be actuated thereby, said gear being operatively connected to the lever for actuating the same; and manually controlled means engageable with said gear for holding the teeth of the same disengaged from the worm member. 115

40 12. In a hand brake mechanism, the combination with a rotary chain-winding member; of a rotary driving member; a reciprocating clutch operatively connecting said winding member and driving member; a manually actuated worm member operatively meshing with the driving member for rotating the same in reverse directions; a pivoted lever for reciprocating said clutch; an oscillatory gear having a toothed section engageable with the worm member and actuated thereby, said gear being operatively connected to the lever for actuating the same; and manually controlled means engageable with said gear for yieldingly urging the toothed section thereof toward and into engagement with the worm member. 120

45 13. In a hand brake mechanism, the combination with a rotary chain-winding member; of a rotary driving member; a reciprocating clutch operatively connecting said winding member and driving member; a manually actuated worm member operatively meshing with the driving member for rotating the same in reverse directions; a pivoted lever for reciprocating said clutch; an oscillatory gear having a toothed section engageable with the worm member and actuated thereby, said gear being operatively connected to the lever for actuating the same; and manually controlled means displaceable to two different positions and engaged with said gear in one position to hold the gear with the toothed section thereof disengaged from the worm, and engaged with the gear in the other position to bring the toothed section of the gear into mesh with the worm member. 125

50 14. In a hand brake mechanism, the combination with a rotary chain-winding member; of a rotary driving member; a reciprocating clutch operatively connecting said winding member and driving member; manually actuated rotary means in constant engagement with the driving member for rotating the latter in reverse directions; and movable means operated by said manually actuated means during rotation of the driving member for engaging and disengaging said clutch. 130

55 15. In a hand brake mechanism, the combination with a rotary chain-winding member; of a rotary driving member; a clutch operatively connecting said winding member and driving member; manually actuated rotary means operatively connected to said driving member, said rotary means being rotatable in reverse directions to rotate the driving member in reverse directions; os- 135

60 16. In a hand brake mechanism, the combination with a rotary chain-winding member; of a rotary driving member; a reciprocating clutch operatively connecting said winding member and driving member; manually actuated rotary means operatively connected to said driving member, said rotary means being rotatable in reverse directions to rotate the driving member in reverse directions; os- 140

65 17. In a hand brake mechanism, the combination with a rotary chain-winding member; of a rotary driving member; a reciprocating clutch operatively connecting said winding member and driving member; manually actuated rotary means operatively connected to said driving member, said rotary means being rotatable in reverse directions to rotate the driving member in reverse directions; os- 145

70 18. In a hand brake mechanism, the combination with a rotary chain-winding member; of a rotary driving member; a reciprocating clutch operatively connecting said winding member and driving member; manually actuated rotary means operatively connected to said driving member, said rotary means being rotatable in reverse directions to rotate the driving member in reverse directions; os- 150

5 oscillatory means for actuating said clutch, said oscillatory means being operated by the rotary means when the latter is rotated in one direction; and cooperating means on said oscillatory means and rotary means for disengaging the oscillatory means from said rotary means when the latter is rotated in the reverse direction.

16. In a hand brake mechanism, the combination with a rotary chain-winding member; of a 10 rotary driving member; a clutch operatively connecting said winding member and driving member; manually actuated rotary means operatively connected to said driving member, said rotary means being rotatable in reverse directions to 15 rotate the driving member in reverse directions; oscillatory means for actuating said clutch, said oscillatory means being operated by the rotary means when the latter is rotated in one direction; and cooperating means on said oscillatory means 20 and rotary means for holding the oscillatory means in inoperative position when said rotary means is rotated in the reverse direction.

17. In a hand brake mechanism, the combination with a rotary chain-winding member; of a 25 rotary driving member; a clutch operatively connecting said winding member and driving member; manually actuated rotary means operatively connected to said driving member, said rotary means being rotatable in reverse directions to 30 rotate the driving member in reverse directions; oscillatory means for actuating said clutch, said oscillatory means being operated by the rotary means when the latter is rotated in one direction; and cooperating means on said oscillatory means 35 and rotary means for disengaging the oscillatory means from the rotary means and holding the oscillatory means in inoperative position throughout rotation of said rotary means in the reverse direction.

40 18. In a hand brake mechanism, the combination with a rotary chain-winding member; of a

worm gear; a reciprocating clutch operatively connecting said worm gear and chain-winding member; a worm meshing with said gear; means for rotating said worm in reverse directions; an oscillatory member having interrupted worm gear teeth thereon adapted to mesh with the worm; and means connecting said oscillatory member and clutch for actuating the latter.

19. In a hand brake mechanism, the combination with a rotary chain-winding member; of a 80 worm gear; a reciprocating clutch operatively connecting said worm gear and chain-winding member; a worm meshing with said gear; means for rotating said worm in reverse directions; an oscillatory member having interrupted worm gear teeth thereon adapted to mesh with the worm; and a lever connected to the clutch for reciprocating the latter, said lever having a lost motion connection with the oscillatory member.

20. In a hand brake mechanism, the combination with a rotary chain-winding member; of a 85 worm gear; a reciprocating clutch operatively connecting said worm gear and chain-winding member; a worm meshing with said gear; means for rotating said worm in reverse directions; an oscillatory member having interrupted worm gear teeth thereon adapted to mesh with the worm; a lever connected to the clutch for reciprocating the latter, said lever having a lost motion 90 connection with the oscillatory member; and a 100 weighted lever swingable to two different positions, said weighted lever in one position having shouldered engagement with the oscillatory member for holding the latter in inoperative disengaged relation with respect to the worm, said 105 weighted lever in the other of said positions having shouldered engagement with the oscillatory member to move the latter with respect to the worm in a direction to engage the teeth of the 110 oscillatory member with the worm.
